(57) CLAIM

The ornamental design for a drill bit container, as shown and described.

DESCRIPTION

FIG. 1 is a perspective view of a drill bit container showing my new design;

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is the opposite side view of FIG. 6 thereof;

FIG. 8 is a perspective view of an alternate embodiment of a drill bit container showing my new design;

FIG. 9 is a front view thereof;

FIG. 10 is a rear view thereof;

FIG. 11 is a top view thereof;

FIG. 12 is a bottom view thereof;

FIG. 13 is a side view thereof; and,

FIG. 14 is the opposite side view of FIG. 13 thereof.

The trademark BOSCH is a registered trademark of the Bosch Tool Company.
